UNITED STATES PATENT OFFICE.

ELMER P. SACREY, OF PHILADELPHIA, PENNSYLVANIA, ASSIGNOR TO WILLIAM F. FISCHER, OF PHILADELPHIA, PENNSYLVANIA.

GRINDING-MACHINE.

1,182,321.

Specification of Letters Patent.

Patented May 9, 1916.

Application filed May 12, 1915. Serial No. 27,483.

To all whom it may concern:

Be it known that I, ELMER P. SACREY, a citizen of the United States, residing in the city of Philadelphia, county of Philadelphia, and State of Pennsylvania, have invented certain Improvements in Grinding-Machines, of which the following is a specification.

My improvements in grinding machines relate more particularly to means for truing grinding wheels, and have the purpose, generally stated, of providing mechanism of simple, accurate, efficient, readily operable, and readily adjustable character adapted for truing the peripheries of grinding wheels of different sizes to desired contours, preferably such that the periphery of the wheel intersects in an arc a plane passed through the axis of the wheel, and facing the wheel's adjacent surfaces to conical or conoidal form.

The characteristic construction and mode of operation of the preferred form of my mechanism for effecting the above purpose of my invention, are disclosed in the following description and the accompanying drawings in illustration thereof.

In the drawings, Figure 1 is a top plan view of part of a grinding machine having my improvements applied thereto; Fig. 2 is a broken side elevation of a machine embodying the construction of Fig. 1; Fig. 3 is a top plan view of my improved mechanism detached; Fig. 4 is a vertical sectional view of the same taken on the line 4—4 of Fig. 3; and Fig. 5 is a vertical sectional view taken on the line 5—5 of Fig. 3.

The mechanism illustrated in the drawings comprises a machine 1 having a grinding wheel 2 for shaping work carried by the holder 3, and it will be understood that the use of such wheels reduces their diameters and renders them irregular or untrue in peripheral contour as a result of wear, which necessitates truing the cutting surface and renders it important to have efficient truing mechanism that is accurate as well as adjustable to varying conditions. These desiderata are effected by my im-

provements which are embodied in the mechanism comprising the bed 4 fixed on the machine 1 in the plane of the wheel 2; the bed plate 5 pivotally connected to the bed 4 by the bolt 6 and having a spirally toothed segment 5' movable laterally in the recess 4' of the part 4 by the worm shaft 7 journaled in the part 4; the slide 8 having the dovetail groove 8' movable on the longitudinal dovetail way 5'' of the plate 5; the screw 9 adapted to feed into the plate 5 and swiveled in the bearing 8'' on the slide 8 to move the latter longitudinally; the plate 10 which is held on the slide 8 by the screw stud 11 having the circular head sections 11' affording a bearing whereby the plate is adapted to be oscillated; the guide rods 12 supported by brackets 13 on the sides of the plate 10; the slide 14 having the bearings 14' movable on the rods 12; the turret 15 (with the standard 15' thereon provided with a cutting tool 15'') which is engaged on the slide 14 in revolute relation thereto by the screw stud 16 having the circular head sections 16'; the shaft 17 journaled on the plate 10 and turned by the handle 17'; the pinion 17'' on the shaft 17 which engages a rack 14'' on the slide 14 to reciprocate the latter; a coiled spring 18 on the shaft 17 with one end fixed thereto and the other engaging the plate 10 to turn the pinion 17'' so as to draw back the slide; the lever 19 which is fulcrumed on a stud 10' on the plate 10, the lever being provided with the longitudinal slot 19' engaging a stud 8a on the slide 8 and the cam slot 19'' having sides with sections 19a approximately parallel to a line through the parts 8a and 10' and sections 19b approximately parallel to the rods 12, and a roller 20 fixed on the turret 15 through the stud 16 and lying between the parallel side sections of the slot 19'.

When, as a result of use or for any reason, it becomes desirable or necessary to true the wheel 2, the slide 8 (which is drawn back to hold the truing mechanism away from the wheel during the latter's use) is moved up to the wheel by means of the

screw 9 and centered in the plane of the wheel by turning the worm shaft 7. The tool 15" being thus disposed at the proper distance from the periphery of the wheel 2 5 for effecting the desired operation, the turret 15 is turned by means of the handle 15^a thereon and the tool 15" is thus oscillated through an arc of 180 degrees so as to give the wheel's periphery a true surface 10 intersecting its axial planes in semi-circular arcs, the oscillatory movement of the turret being limited by the engagement of its handle 15^a with stops 14" on the slide 14 and by reversing the position of the plate 10. The 15 periphery of the wheel having been "trued," the revolving wheel is conically faced down to the limits of the periphery by reciprocating the slide 14 on the rods 12 through the action of the pinion 17" on the rack 14" 20 due to operating the shaft 17, handle 17^a, and spring 17^b. In this operation, the mechanism is in the position shown in Fig. 1, with the rods 12 parallel to the elements 25 of the cone to be formed on the right side of the wheel when facing the wheel's right side, and is thrown to the reverse position, with the rods parallel to the cone elements 30 to be formed on the left side of the wheel when the left side of the wheel is to be faced, the turret being reversed to place the 35 tool 15" on the opposite sides of the wheel for the two facing operations. When the handle 15^a is turned and the turn table 15 is oscillated on the slide 14, the roller 20, fixed eccentrically to the axis, acts between the parallel surfaces of the cam 19" to oscillate the lever 19, which acts through the stud 10' to oscillate the plate 10 so that at the limits of its turning operations the 40 tool 15" can be reciprocated, by reciprocating the slide 14 on the rods 12, to face the corresponding side of the wheel.

Having described my invention, I claim:

1. The combination with a wheel, of 45 mechanism comprising a tool, a tool holder having an oscillatory action for moving said tool in a curved path in contact with the periphery of said wheel, and oscillatory mechanism comprising a reciprocating slide 50 on which said holder oscillates and by which said tool is adapted for facing said wheel.

2. The combination with a wheel, of 55 mechanism comprising a tool, a tool holder having an oscillatory action for operating said tool in a circular arc in contact with the periphery of said wheel, a slide on which said holder is mounted, and oscillatory guiding means for said slide.

60 3. The combination with a wheel, of mechanism comprising a tool for truing said wheel, a holder having an oscillatory movement for turning the periphery of said

wheel, a slide carrying said holder for reciprocating said tool and means whereby 65 said slide is shiftable to different positions for permitting the reciprocation of said tool in contact with opposite sides of said wheel.

4. The combination with a wheel, of mechanism comprising a tool for cutting said wheel, a holder adapted for moving said tool across the periphery of said wheel, and a slide on which said holder is movable and whereby said tool is adapted to be reciprocated to face the sides of said wheel adjacent to its periphery, said holder turning on an axis transverse to the direction of movement of said slide.

5. The combination with a wheel, of guiding means having an oscillatory movement, a slide mounted on said guiding means, a turret adapted to turn on said slide, a tool movable by said turret in contact with the periphery of said wheel, and means for reciprocating said slide.

6. The combination with a wheel, of a slide adapted to reciprocate in the plane of said wheel, a guide adapted to oscillate on said slide, a slide adapted to reciprocate on 90 said guide, a turret adapted to turn on said slide last named, a tool carried by said turret, and means for simultaneously turning said turret and guide in opposite directions.

7. The combination with a wheel, of supporting means movable laterally relatively to said wheel, a slide adapted to reciprocate on said supporting means in the plane of said wheel, guiding means pivoted on said supporting means so as to oscillate transversely to the plane of said wheel, a slide adapted to reciprocate on said guiding means toward and from the periphery of said wheel, a turret pivoted on said second named slide, a tool carried by said 105 turret for acting on said wheel, and means for turning said turret and guiding means in opposite directions whereby said tool is adapted to be operated in the arc of a circle to round the periphery of said wheel and 110 in lines angular to the plane of said wheel for conically facing the sides of said wheel adjacent to its periphery.

8. The combination of oscillatory guiding means, supporting means adapted to reciprocate on said guiding means, tool holding means adapted to oscillate on said supporting means, and means for simultaneously turning said guiding means and tool holding means in opposite directions.

9. The combination of oscillatory guiding means, supporting means adapted to reciprocate on said guiding means, tool holding means adapted to oscillate on said supporting means, and means comprising a lever connected with said guiding and hold-

ing means whereby they are simultaneously thrown in opposite directions.

10. The combination of oscillatory guiding means, supporting means adapted to reciprocate on said guiding means, tool holding means adapted to oscillate on said supporting means, and means comprising a lever provided with a cam fulcrumed

on said guiding means and a device connecting said holding means with said cam ¹⁰ whereby the movement of said guiding and holding means is effected.

In testimony whereof I have hereunto set my name this 11th day of May, 1915.

ELMER P. SACREY.
